UNITED STATES PATENT OFFICE

WILLIAM H. FULTON, OF ORANGE, NEW JERSEY, ASSIGNOR TO THE PARADON COMPANY, OF ARLINGTON, NEW JERSEY, A CORPORATION OF DELAWARE

METHOD OF AND MEANS FOR STERILIZING

Application filed July 24, 1930. Serial No. 470,525.

This invention relates to sterilizing apparatus and particularly to a type which, among other uses, is well adapted for use in sterilizing bottles.

5 In the sterilizing processes in use today for sterilizing bottles of various types, it is necessary after the sterilizing and washing operations to rinse the bottle with both hot and cold water before the bottle is used. While 10 the bottle may have been perfectly clean and sterile after the completion of the sterilization process, the cold rinse water may have a high bacteriological content and consequently at the close of the operation the bottle is, at the 15 best clean, but in no sense can it be said that it is sterile.

This condition may result in the liquid, which is later placed in the bottles, becoming a culture for the bacteria in the particles of 20 rinse water which remained in the bottles at the time of filling.

The primary object of this invention is the provision of a new and improved method and apparatus for sterilizing.

25 Another object of the invention is the provision of an improved sterilizing device for use in connection with washing machines in common use.

Another object of the invention is the provision 30 of a sterilizer wherein a measured amount of sterilizing agent is placed in water and carried directly to the surface to be sterilized.

Another object of the invention is the provision 35 of a sterilizer device having a water inlet and a water outlet, a chamber for the collection of a sterilizing agent and a connection to the water outlet from the chamber to deliver the agent to the water.

40 Other and further objects of the invention will be apparent to those skilled in the art from a reading of the complete specification and claims.

45 In the accompanying drawings, I have illustrated an embodiment and an application of my invention wherein,

Figure 1 illustrates a diagrammatic showing of the operation of my invention.

50 Figure 2 is a view of a portion of a bottle

washing machine showing the connections for my invention.

Figure 3 is a cross section on the line 3—3 of Figure 2.

Throughout the drawings and specification, the same reference characters refer to the same or similar parts.

Referring particularly to Figure 1 wherein the important features of this embodiment of my invention are illustrated, 10 designates the inlet connection of the fluid which acts as a vehicle for the sterilizing agent and in this case represents a pipe connection to a service water main. The valve 11 is connected to the connection 10 and controls the intermittent 55 flow as will be later described.

The water after passing the valve 11 passes through the passage 12 and into the jet 13. The restricted delivery end of the jet 13 causes the speed of flow to be increased at 70 this point. The delivery end of the jet 13 is located in the mixing chamber 14 where the sterilizing agent is delivered, as will be later described. The outlet 15 is provided for the delivery of the fluid and sterilizing agent 75 as will be later described.

The sterilizing agent which is described in this embodiment as the gas chlorine, is delivered through a tube 16 from a suitable source of supply. This tube 16 is connected 80 to a tank through a suitable pressure control valve such as is common in the art.

When an agent such as chlorine is used, it is necessary to have all connections and parts which might contact with the agent, of a 85 material which will not be affected by the agent. Accordingly, the tubes for the passage of the agent are made of silver and the body portions are made of hard rubber.

The agent supply pipe 16 of silver passes 90 through a removable gland 17 of silver. This removable gland 17 is held in place by a brass follower 18 which is screw-threadedly connected to a brass ring 19. Screw-threadedly and soldered to the ring 19 is a silver 95 tube 20 having a passage 21 and a small valve seat opening 22.

The ring 19 rests on the bottom of a counter-sunk opening in the body member 23 of hard rubber. The lower end of the tube 100

20 is screw-threadedly connected to a brass receiver 24 which fits a counter-sunk opening similar to that occupied by the ring 19.

A control valve 25 with an end 25^a which 5 fits into the opening 22, extends along the lower interior of the tube 20, and is made of silver. A gland 26 forces the packing 27 tightly against the outside of the control valve 25 and seals it in the tube 20. A follower 10 lower 28 of brass holds the gland 26 and packing 27 in place and is screw-threadedly in the receiver 24. The interior of the follower 28 is threaded to receive the threads of the thumb-piece 29 which is tightly threaded to and controls the movement of the valve 25. The end 25^a of the valve 25 has a beveled tip which serves as a delicate control for the agent passing through the passage 21 and then through the openings 20^a 15 in the tube 20.

In the hard rubber body member 23 and about the holes 20^a, is an enlarged opening 30. This opening 30 connects to a passage 31 which extends through the body member 25 23 to a cutaway portion 32 of a hard rubber plug 33. This plug 33 is screw-threaded in the body portion 23 as shown at 33^a.

At another part of the body portion 23 and connected to the passage formed by the cut 30 away portion 32 so as to be connected to the passage 31, is a passage 34 which leads to the passage within a silver tube 35. This silver tube 35 extends into a chamber which has a transparent wall as the glass tube 36. 35 This tube 36 is held at its upper end by a ring 37 and a packing 38 prevents a crushing action by the ring against the flange 36^a of the tube 36. The lower end of the tube 36 extends into a water seal cup 39 for a purpose to be later described.

Extending into the chamber within the tube 36 and to control the capacity of the sterilizing agent chamber, to be described, is the silver control tube 40. This tube extends 45 upwardly through an opening filled with asbestos packing 41. Its upper end is connected to a control rod 42. A handle 42^a is placed on the end of the rod 42.

Surrounding the tube 40 is a hard rubber 50 plug 43 with a tube 43' having a space 43^a therein surrounding a substantial portion of the length of the rod 42. At a point near the upper end of the tube 40 and adjacent the point where it is connected to the rod 42, 55 are openings 44. These openings are always in communication with the space 43^a whether the tube 40 is in a high or low position.

At the bottom of the tube 43 is a silver washer 48^b and at the top is a silver washer 60 43^c. The lower washer 48^b rests against the packing 41 already described and the upper washer 43^c holds the bottom of the packing 45 of asbestos or any other suitable material. A packing nut 46 presses downwardly on the 65 packing 45 and holds the same in place. The

packing nut is of brass and screw-threaded into the hard rubber plug 43.

With shoulders below the packing 41 and the tube 43' pressed thereon by the packing 45 through the packing nut 46, an equalization between the packings 41 and 45 is maintained. The tube 43' adjacent its lower end, has openings 47 to permit passage into the chamber 48 below the plug 43.

Extending from the chamber 48 is a passage 49 which extends to a water jet vacuum device now to be described.

An auxiliary water supply 50 delivers water through a flanged connection 51 which is provided with a flange 51^a. A brass strainer fitting 52 of brass rests on the top of the body member 23 and is provided at its upper end with screw threads on its outer surface.

A flanged screen holder 53 carrying the screen 54, coacts with the connector 51 and the top of the strainer fitting 52, these parts all being held in place by the interiorly threaded collar 55.

The strainer fitting 52 rests on the top of the body member 23 in a slightly depressed space with its lower opening 52^a opposite a corresponding opening in the body 23. In this opening is placed an injector nozzle 56, the member 52 being counter bored to receive the flange 56^a. Integral or in close contact with the nozzle 56 is the tube 57 which extends through the bottom of the body member 23 and connects to a waste pipe 58.

Adjacent the opening of the nozzle 56 and in the wall of the pipe 57, are openings 57^a 100 into the annular space 59. This space 59 has constant communication with the passage 49, already described.

It will thus be seen that there is a passage 105 from the tube 16, through the tube 21, past the valve 25^a, through the openings 20^a, into the space 30, through the passage 31, into the space 32, through the passage 34, the tube 35, the chamber in the tube 36, into the tube 40, through the openings 44 to the chamber 48, through the passage 49, to the space 59 and through the openings 57^a into the tube 57 where the agent may be carried off with the waste water. This whole course is followed only in case there is an excess of the sterilizing agent as chlorine and normally does not go beyond the chamber in the tube 36 which will now be described.

In addition to the auxiliary flow of water 115 through the tube or pipe 50, there is a second auxiliary flow through the pipe 59 into the chamber 60 within the water seal cup 39. Also within the box 39 is a chamber 61, the two chambers being connected with an overflow opening 62. The tube 58 extends entirely through the cup 39 and where it passes through the bottom is provided with a clearance 62' from the side of the opening. Through this clearance passes the water 125 which overflows from the chamber 60 into the 130

chamber 61 through the connecting opening 62.

Assuming the water to be turned on in the two auxiliary flows through the pipes 50 and 59, the water level will rise in the chamber 60 to the level of the overflow opening 62. The water supply through the pipe 59 should not, however, be great enough to produce an overflow of water through the opening 62 as this would be an unnecessary waste of water. But since the jet of water through the nozzle 56 will create a partial vacuum in the passage 49, gas will be drawn off by way of the tube 40 until the water level in the tube 36 rises to the bottom of the tube 40. Then water will be drawn up through the tube 40 by the injector nozzle 56. The surface of the water at the bottom of sterilizing agent chamber of the tube 40, becomes the lower movable wall or bottom of the chamber which collects the sterilizing agent during the time the main water supply is cut off.

If now the knob 42^a be used to raise the height of the lower end of the tube 40, the injector nozzle 56 will exhaust the air or gas within the tube 36 until the water level reaches the bottom of the tube.

With both auxiliary water flows turned on, let us now assume the sterilizing agent to be admitted through the pipe 16 and under control of the control valve 25^a. The agent will follow the course already outlined until it reaches the chamber in the tube 36. If the flow of agent is too great, it presses down the lower water wall of the chamber to a point below the bottom of the tube 40, the excess agent being drawn up through the tube 40 and wasted in the pipe or tube 58.

Having described the course through which the sterilizing agent reaches its collecting place in the chamber within the tube 36, I will now describe that part of the apparatus which delivers the agent to the mixing chamber 14 and the operation of the parts during such delivery.

In one side of the cutaway space 32 is an opening to a passage 63 in the plug 33. This passage 63 extends to a small passage 64 in a plug 65 which plug is screw-threaded in the end of the passage 63. The face of this plug forms a valve seat for the inlet valve 66 carried by the valve screw 67 which is operated by the valve handle 68.

The passage 64 is, when the valve 66 is raised, in communication with the chamber 69. A passage 70 leads from the chamber 69 through the plug 33 to the chamber 71 which is formed between the bottom of the plug and the body member 23. In the bottom of this chamber is an opening to a passage 72 which leads to a space 73 between a silver tube 74 and the wall of a rubber bushing 75, this latter being enclosed in a metal housing 76. Openings 74^a are provided to admit the ster-

ilizing agent to the mixing chamber 14 as already mentioned.

The nozzle 13 already described is constructed of silver and is held in place, through its flange, by the threaded bushing 77 which is threaded into the bushing 75.

The bushing 75 is held in place by the threaded plug 78 which carries a silver sleeve 79 at the end of which is the delivery opening 15 for the water and sterilizing agent mixture.

Assuming the water to be turned on through the valve 11 and the other auxiliary water to be turned on and the sterilizing agent being fed into the system by the pipe 16 as already described, the operation is as follows:

The chamber in the tube 36 is defined by the inner surfaces of the tube, the top by the level of the bottom of the tube 35 and the bottom by the water level at the bottom of the tube 40.

The chamber contains the sterilizing agent used by the water delivered by one operation between the time of opening of the valve 11 and its closing.

When the valve 11 opens, the water passing through the jet nozzle 13, creates a partial vacuum in the space 73, by drawing the agent through the openings 74^a.

This draws the gas from the collection chamber within the tube 36, back through the tube 35 to the passage 34, to the space 32, into the passage 63, through the passage 64, past the valve 66, into the chamber 69, out through the passage 70 to the chamber 71, through the passage 72 to the space 73 and through the openings 74^a. The closing of the valve 11 and the capacity of the collecting chamber are so relatively controlled that when the water level of the collecting chamber reaches the bottom of the tube 35, the valve 11 will close. The sterilizing agent which enters during the time the collecting chamber is being exhausted, passes from the passage 31, through the space 32, to the passage 63 direct, without going first to the collecting chamber.

In this way the amount of sterilizing agent delivered during each cycle is the sum of the capacity of the collecting chamber plus the amount of the agent brought in during the time the valve 11 is open.

In order to determine whether or not sufficient of the sterilizing agent is being delivered to the water, it is necessary to make some kind of a test. In the case of chlorine in water, it has been found that a residual of from .1 to .5 parts of chlorine in 1,000,000 parts of water is a complete assurance of a sterile condition. In testing, a sample of the water to be tested has added to it, ortho-toluidine. A greenish tint results varying in intensity with the amount of chlorine present in the water. The sample produced

is compared with the colors of samples of known residual strengths. In this way it is possible to make a test at any time and to immediately determine whether or not an effective sterilization has been produced.

By watching the action of the gas in the collecting chamber and making tests of the residual strength of the delivered mixture, it is possible to control the exact amount of the sterilizing agent used and without any waste. If the water delivered is found to be more highly charged than necessary, the tube 40 is raised to decrease the size of the collecting chamber and the control valve 25^a adjusted 15 by the control knob 29 to reduce the amount delivered. When it is observed through the glass tube 36 that some of the sterilizing agent is escaping through the tube 40 due to the collecting chamber filling too fast, the 20 control valve 25^a by the knob 29 is adjusted to further restrict the entrance of the agent.

If the collecting chamber does not fill during each cycle as evidenced by the fact that the water level does not fall to the bottom of the tube 40, the valve 25^a should be 25 opened.

Attention is called to the fact that should 30 operation of the apparatus be interrupted for a time, the first charge of water after resumption of the operation will contain no more of the sterilizing agent than the following charges. During the time of interruption, the excess of sterilizing agent will simply waste through the pipe 40, and out past the 35 auxiliary injector.

The gas inlet valve 66 should receive careful adjustment and should be so adjusted, by turning the handle 68, that during the time the main water supply is turned on through 40 the valve 11, there will be just sufficient time to raise the level of the water in the collecting chamber to the height of the bottom of the tube 35, by the time the water is shut off at the valve 11. In this way, a constant flow of 45 gas will be delivered to the chamber 14 and all of the water will be sterile when delivered.

In utilizing my invention for different purposes, the necessary changes in connections and in time of operation will have to be made. 50 In the present illustration I have shown a portion of a bottle washing machine, in the operation of which as a last step, my invention is used to sterilize the clean bottles.

In the operation of one form of bottle washing machine, it takes twelve seconds for the 55 completion of a cycle of operation, there being six seconds to move the bottles out of position and the next set into position, the remaining six seconds being utilized for sterilizing.

In Figure 2, 100 represents the bottles arranged on an endless carrier which presents the bottles to the washing operation (not shown) and then to the sterilizing apparatus 60 herein described.

In the illustrated form, it will be understood that the bottles are washed and sterilized in groups of four and that there are two rows of bottles moving side by side. Each time the bottles are moved, they move two 70 spaces.

The delivery end of the plug 78 has its threaded end connected to the manifold 101 by the pipe 102. The manifold 101 has two pipes 103 extending therefrom, each with 75 two spray nozzles 104 making four in all.

The operating wire or rod 104 is connected to the cam-operated mechanism of the device in such a manner that when the bottles are stopped over the spray nozzles 104, the rod 80 104 will be pulled, operating the quick-acting valve 11 to start the sterilizing operation.

At the end of the six second interval, the sterilizing operation will be complete and the quick acting valve will be closed for six seconds during which time, the collecting chamber will collect its sterilizing agent for the sterilization of the next set of four bottles. At the same time the endless carrier will be moving the next set of bottles into position to 90 be sterilized. If because of a broken bottle or for any other cause the machinery stops, the first charge of water and chlorine after the stop, will be no stronger than it would have been if the operation had not been interrupted.

While an embodiment of my invention has been described in detail in connection with the sterilization of bottles, it is to be understood that I do not limit myself to these details or this use and that modifications and changes may be made and the invention used in sterilizing operations other than in bottles without departing from the spirit of the invention and within the scope of the appended claims. 100

Having described my invention, what I claim and desire to secure by Letters Patent is:—

1. The process of sterilizing which comprises the delivery of a measured amount of a gaseous sterilizing agent from a chamber of controllable capacity into a measured amount of water and the intermittent delivery of the water and sterilizing agent to the body or bodies to be sterilized. 110

2. The process of sterilizing which comprises the delivery of a measured amount of water intermittently to a body or bodies to be sterilized, the delivery of a gaseous sterilizing agent from a chamber of controllable capacity in a measured amount into the water stream when turned on, the agent being collected for delivery during the time the water stream is turned off. 120

3. The process of sterilizing which comprises the delivery of a measured amount of sterilizing agent from a chamber of controllable capacity into a measured amount of fluid and the intermittent delivery of the fluid 130

and sterilizing agent to the body or bodies to be sterilized.

4. The process of sterilizing which comprises the delivery of a measured amount of liquid intermittently to a body or bodies to be sterilized, the delivery of a sterilizing agent from a chamber of controllable capacity in a measured amount into the liquid stream, when turned on, the agent being collected for delivery during the time the liquid stream is turned off.

5. The process of sterilizing surfaces which comprises controlling the flow of a gaseous sterilizing agent from a chamber of controllable capacity by a sight feed and injecting this gas into a flow of water and the delivery of the gas and water to and along the surface to be sterilized.

6. The process of sterilizing surfaces which comprises controlling and measuring the flow of a gaseous sterilizing agent from a chamber of controllable capacity by a sight feed and injecting this gas into a flow of water and the delivery of the gas and water to and along the surface to be sterilized.

7. The process of sterilizing which comprises the delivery of a measured amount of gaseous sterilizing agent into a variable capacity water seal chamber, then drawing off the agent and mixing it with a water flow and delivering the agent and water to the body to be sterilized.

8. The process of sterilizing bottles which comprises the delivery of a measured amount of gaseous sterilizing agent into a variable capacity chamber, of then connecting the chamber to a water flow and mixing the agent and water together, delivering the mixture as a spray to the bottle interior and turning off the water flow when the operation for that bottle is completed.

9. A sterilizing apparatus comprising a water inlet, a gaseous sterilizing agent inlet duct, a variable capacity gas measuring and delivering chamber for receiving and delivering the agent in measured quantities, an outlet for the water and agent and a connection from the chamber to the outlet.

10. A sterilizing apparatus comprising a water inlet, a sterilizing agent inlet duct, a chamber for receiving the agent, means for controlling the capacity of the chamber, an outlet for the water and agent and a connection from the chamber to the outlet.

11. A sterilizing apparatus comprising a water inlet, a sterilizing agent inlet duct, a chamber for receiving the agent, the chamber having a fluid wall, means for varying the limit of the position of the fluid wall, an outlet for the water and agent and a connection from the chamber to the outlet.

12. A sterilizing apparatus comprising a water inlet, a sterilizing agent inlet duct, a chamber for collecting the agent, the chamber having a movable wall, means for removing

excess agent beyond a predetermined amount, an outlet for the water and agent and a connection from the chamber to the outlet.

13. A sterilizing apparatus comprising a water inlet, a sterilizing agent inlet duct, a chamber of variable capacity for receiving the agent, the chamber having a transparent wall, means visible through the transparent wall for controlling the capacity of the chamber, an outlet for the water and agent and a connection from the chamber to the outlet.

14. A sterilizing apparatus comprising a water inlet, a sterilizing agent inlet duct, a chamber having a transparent wall, a fluid bottom for the chamber, a tube extending into the chamber and having an opening at the predetermined lower limit of the chamber bottom, suction means attached to the tube and a connection from the chamber to the outlet.

15. A sterilizing apparatus comprising a water inlet, means for giving an intermittent flow to the water through the inlet, a gaseous sterilizing agent inlet duct, a variable capacity gas measuring and delivering chamber for receiving and delivering the agent in measured quantities, a mixing chamber for mixing the water and agent, an outlet for the mixing chamber, and a connection from the receiving chamber to the mixing chamber.

16. A sterilizing apparatus comprising a water inlet, means for giving an intermittent flow to the water through the inlet, a sterilizing agent inlet duct, a chamber for receiving the agent, means for controlling the capacity of the chamber, an outlet for the water and agent and a connection from the chamber to the outlet, operative when the intermittent operating means is in operation.

17. A sterilizing apparatus comprising a water inlet, means for giving an intermittent flow to the water through the inlet, a sterilizing agent inlet duct, a chamber for receiving the agent, a mixing chamber for mixing the water and agent, the receiving chamber having a fluid wall, means for varying the limit of the position of the fluid wall, an outlet for the mixing chamber and a connection from the receiving chamber to the mixing chamber, operative when the intermittent operating means is in operation.

18. A sterilizing apparatus comprising a water inlet, means for giving an intermittent flow to the water through the inlet, a sterilizing agent inlet duct, a chamber for receiving the agent, a mixing chamber for mixing the water and agent, the receiving chamber having a movable wall, means for removing excess agent beyond a predetermined amount, an outlet for the mixing chamber and a connection from the receiving chamber to the mixing chamber, operative when the intermittent operating means is in operation.

19. A sterilizing apparatus comprising a water inlet, means for giving an intermit-

5 tent flow to the water through the inlet, a sterilizing agent inlet duct, a chamber for receiving the agent, a mixing chamber for mixing the water and agent, the receiving chamber having a transparent wall, means visible through the transparent wall for controlling the capacity of the receiving chamber, an outlet for the mixing chamber and a connection from the receiving chamber to the 10 mixing chamber, operative when the intermittent operating means is in operation.

15 20. A sterilizing apparatus comprising a water inlet, means for giving an intermittent flow to the water through the inlet, a sterilizing agent inlet duct, a chamber for receiving the agent, a mixing chamber for mixing the water and agent, the receiving chamber having a transparent wall, and a fluid bottom, a tube extending into the chamber and having 25 an opening at the predetermined lower limit of the chamber bottom, suction means attached to the tube, an outlet for the mixing chamber and a connection from the receiving chamber to the mixing chamber, operative when the intermittent operating means is in operation.

30 21. A sterilizing apparatus comprising a water inlet, a variable capacity sterilizing agent inlet duct, a sterilizing agent measuring chamber for receiving and delivering the agent in measured quantities, an outlet for the water and agent, a connection from the chamber to the outlet and a jet in the water course adjacent the delivery end of the connection.

35 40 22. A sterilizing apparatus comprising a water inlet, a sterilizing agent inlet duct, a chamber having a variable capacity for receiving the agent, a passage from the agent inlet duct to the receiving chamber, means for controlling the flow of the sterilizing agent to the chamber, an outlet for the water and agent and a connection from the chamber to the outlet.

45 50 23. A sterilizing apparatus comprising a water inlet, a sterilizing agent inlet duct, a chamber for receiving the agent, means for preventing an excess of agent from remaining in the chamber, comprising a tube extending into the chamber and having an opening, means outside of the chamber for adjusting the position of the opening relative to the top of the chamber, a water injector suction means connected to the tube to remove excess agent, an outlet for the water and agent and a connection from the chamber to the outlet.

55 60 65 24. A sterilizing apparatus comprising a water inlet, a sterilizing agent inlet duct, a chamber for receiving the agent means for conducting a flow of water adjacent the lower portion of the receiving chamber, a tube having an opening adjacent the surface of the water of the chamber, a water jet suction means connected to the tube to normally exhaust water therethrough, a mixing chamber

70 for the water and agent and adjacent the inlet, a water jet adjacent the mixing chamber and in the course of the water flow from the inlet, a connection from the receiving chamber to deliver the agent to the mixing chamber and an outlet for the water and agent.

75 80 85 25. A sterilizing apparatus comprising a water inlet, means operating to supply an intermittent flow to the water through the inlet, a sterilizing agent inlet duct, a chamber for receiving the agent, means for conducting a flow of water adjacent the lower portion of the receiving chamber, a tube having an opening adjacent the surface of the water of the chamber, a water jet suction means connected to the tube to normally exhaust water therethrough, a mixing chamber for the water and agent and adjacent the inlet, a water jet adjacent the mixing chamber and in the course of the water flow from the inlet, a connection from the receiving chamber to deliver the agent to the mixing chamber during operation when the intermittent operating means is in operation and an outlet for the water and agent.

90 In testimony whereof I hereunto affix my signature.
